UNITED STATES PATENT OFFICE.

LEONARD W. SWEET, OF NEW YORK, N. Y.

DESIGN FOR A TABLE-VESSEL.

SPECIFICATION forming part of Design No. 25,139, dated February 11, 1896.

Application filed October 28, 1895. Serial No. 567,197. Term of patent 7 years.

To all whom it may concern:

Be it known that I, LEONARD W. SWEET, a citizen of the United States, and a resident of New York, in the county and State of New York, have invented and produced a new and original Design for a Table-Vessel, of which the following is a full, clear, and exact specification, reference being had to the accompanying drawings which form a part hereof.

This invention relates to a design for a table-vessel especially adapted for use in pouring tea or coffee; and it consists of the novel shape and arrangement herein shown and described.

In the drawings, Figure 1 is a perspective elevation of the vessel embodying the design, and Fig. 2 is a side elevation showing the side directly opposite to the handle.

The design consists of the vessel A. This vessel is characterized by an open-top rounded bowl-shaped body having on one side and below the upper edge a spout *a*, a standard or support *b*, and an outwardly-projecting handle connected to one side of the body on a line substantially at right angles to the spout. 20 25

What I claim as new, and desire to secure by Letters Patent, is—

The design for a table-vessel consisting of the design substantially as shown.

In testimony whereof I have signed my 30 name to this specification in the presence of two subscribing witnesses.

LEONARD W. SWEET.
